UNITED STATES PATENT OFFICE.

ANALDO M. ENGLISH, OF BROOKLINE, AND HOWARD W. GIBBS, OF BOSTON, MASSACHUSETTS, ASSIGNEES TO J. SPAULDING & SONS CO., OF ROCHESTER, NEW HAMPSHIRE, A COPARTNERSHIP COMPRISING MARION L. SPAULDING, OF BOSTON, MASSACHUSETTS, ROLAND H. SPAULDING AND HUNTLEY N. SPAULDING, BOTH OF ROCHESTER, NEW HAMPSHIRE, AND LEON C. SPAULDING, OF BUFFALO, NEW YORK.

CRIMPING OR CORRUGATING MACHINE.

1,230,691.

Specification of Letters Patent. Patented June 19, 1917.

Application filed November 15, 1915. Serial No. 61,504.

To all whom it may concern:

Be it known that we, ANALDO M. ENGLISH and HOWARD W. GIBBS, citizens of the United States, and residents of Brookline and Boston, in the counties of Norfolk and Suffolk, respectively, in the State of Massachusetts, have invented an Improvement in Crimping or Corrugating Machines, of which the following description, in connection with the accompanying drawings, is a specification, like characters on the drawings representing like parts.

This invention relates to a crimping or corrugating machine and is herein shown as embodied in a machine for crimping or corrugating the lip of an insole for boots and shoes, for which purpose it is particularly applicable.

The invention has for its object to provide a superior machine for the purpose specified, and one which is simple in construction, easy to operate and with which the insoles may be provided with crimped lips of the same or uniform height.

The invention further has for its object to provide a machine in which one of the crimping tools may be utilized for turning the lip into position to be crimped.

Provision may and preferably will be made for pressing the lip toward the body portion of the insole after the lip has been acted upon by the crimping tools, as will be described.

These and other features of this invention will be pointed out in the claims at the end of this specification.

Figure 1 is a plan of a machine embodying this invention.

Fig. 2, a front elevation of the machine shown in Fig. 1.

Fig. 3, a side elevation looking toward the right in Fig. 2.

Fig. 4, a side elevation looking toward the left in Fig. 2.

Fig. 5, a vertical section on the line 5—5, Fig. 1.

Figs. 6 and 7, details in section on the line 6—6, Fig. 1, and on an enlarged scale, to illustrate the operation of the crimping tools.

Fig. 8, a section on the line 8—8, Fig. 7.

Figs. 9 and 10, details of the oscillating crimping tool, and

Fig. 11, a detail of the device for insuring uniformity in the height of the lip.

Referring to the drawings and particularly to Figs. 6 and 7, *a* represents an insole for use in welted boots and shoes, and preferably made of substantially non-stretchable material, such as hard fiber. The machine which forms the subject of the present invention is designed to turn up a lip *b* on the insole, and provide said lip with transverse crimps or corrugations *c*, shown in Fig. 8.

To this end, the machine is provided with tools for crimping or corrugating the lip *b* transversely, one of said tools being movable toward and from the other and having an oscillatory movement, whereby it acts to turn an uncrimped portion of the lip into position to be crimped, and also forms a crimp or corrugation in a portion of the lip which had been previously turned up into proper position to be crimped.

In the present instance, the oscillating tool is shown as a substantially wide finger 10 on the end of an arm 12, attached to or forming part of a pivot pin or shaft 13, which is mounted to turn in a bearing hub 14. The finger 10 is provided, as shown, with a substantially flat face having in it a plurality of substantially parallel cavities 15, 16, and the arm 12 is shown as substantially triangular in cross-section with the apex of the triangle at the lower edge of said arm.

The crimping tool 10, 12, is oscillated toward and from a coöperating tool, which latter may be made as herein shown of two rods 18, 19, (see Figs. 3, 4 and 8), which in the present instance are connected at their upper ends by a cross bar 20 and are mounted to slide in grooves in a carrier or block 21, secured to a head 22 attached to a lever 23, mounted on a pivot pin or shaft 24 (see Fig. 5), which is journaled in hubs 26 attached to the framework of the machine.

The lever 23 is provided with a laterally extended arm 27 to which the bearing hub 100

14 for the oscillating tool 10, 12 is secured, so that it will be seen that both crimping or corrugating tools are carried by the lever 23.

The oscillating tool 10, 12 is operatively connected with a lever 29 (see Fig. 3), which is effected as herein shown by a link 30 having a ball and socket connection with the lever 29 at one end, and a like connection at the other end with a projection 31 on the arm 12 of the oscillating tool.

The lever 29 is mounted to turn on a pivot pin 32 (see Fig. 5) carried by the hub 33 of the lever 23, so that the lever 29 is capable of being moved independently of the lever 23 to rock or oscillate the tool 10, 12, and effect a transverse crimp or corrugation in the lip *b*, and is also capable of moving with the lever 23 so as to feed the insole by means of the crimping tools.

The movement of the lever 29, which effects the oscillation of the crimping tool 10, 12, is accomplished as herein shown by means of a path cam 35 in one side or face of a wheel or disk 36 mounted on a shaft 37, the path cam 35 having extended into it a roller 38 carried by the lever 29.

The movement of the levers 23, 29, which effects the feed of the insole, is accomplished by cams 40, 41, on opposite faces of the disk 36 near the circumference of the same, which engage rollers 42, 43 (see Figs. 1 and 2) carried by the lever 23 and engaging said cams.

The path cam 35 is suitably shaped and timed to rock the crimping tool 10, 12 forward or toward the coöperating crimping tools 18, 19, from substantially the position shown in Fig. 6 into that shown in Fig. 7, so as to form a crimp, marked 43 in Fig. 8, 40 in an uncrimped portion of the lip *b*, and to retain the crimp *c*, which was previously formed, from being distorted while the crimp 43 is being formed.

The oscillating tool 10, 12, may and preferably will have coöperating with it a backing member, shown as an arm 45, which is attached to the lever 23, and is provided as shown with a curved portion 46 (see Fig. 6), which conforms to the curvature of the upper surface of the arm 12 of the oscillating crimping tool.

It will thus be seen that the oscillating crimping tool 10, 12 in the machine herein shown, on its forward movement from the position shown in Fig. 6 into that shown in Fig. 7, serves a three-fold purpose, to wit: it serves to prevent distortion of a previously formed crimp *c* by the coöperation of the cavity 16 and the rod 19, and forms a new crimp 43 by the coöperation of the cavity 15 and rod 18, and also serves to turn over an uncrimped portion of the lip of the insole into an inclined position ready to be crimped. The oscillating crimping tool co-

operates with the tools 18, 19 to feed the insole so as to bring the uncrimped turned-over portion of the lip into position to be crimped.

After the insole has been fed forward, the insole is held stationary as will be described, and the oscillating tool 10, 12, is then moved away from the tools 18, 19, from substantially the position shown in Fig. 7 into substantially the position shown in Fig. 6 so as to release the lip, and thereafter the crimping tools are moved laterally in the opposite direction to the feeding movement to bring the crimping tools into their starting position, in which they are in proper position to engage the last-formed crimp 43 and to form a new crimp in the turned-over portion of the lip.

It is desirable that the lip *b* in the completed insole should be of uniform or substantially uniform height throughout its length, and provision is made for effecting this result. To this end, a gage or device is provided with which the free edge of the uncrimped portion of the lip is designed to be engaged, when the latter is being turned over by the oscillating tool.

In the present instance, we have shown one construction of gage for this purpose, which consists of a finger 50 on a block 51 (see Fig. 11), which is attached to or forms part of a stationary plate or bar 52, secured to the framework of the machine, and having a substantially flat under surface and an inclined upper surface 53, which forms with the flat under surface a substantially thin edge 54, which is designed to enter between the lip *b* in its flat condition and the feather 55 of the insole, and initially open up the lip when the insole is placed in the machine. The inclined upper surface 53 serves as a wedge to turn up the lip *b* from its substantially flat position parallel with the feather 55 of the insole, and the extent to which the lip is turned up is limited by the finger 50 with which the edge of the lip *b* engages, and when the edge of the lip engages the underside of the finger the said edge is turned over slightly, and the lip is prevented from being turned up any further, and is thus made of uniform or substantially uniform height throughout its length, which is desirable, as it enables the insole to be sewed to the upper of boots and shoes on the machines now used in shoe factories for this purpose with uniform results.

The stationary plate 52 extends over a section 57 of a work support or table 58, and coöperates with the section 57 to grip the feather 55 of the insole and hold the latter firmly against movement at the end of the feeding movement of the insole, and while the lip is released by the crimping tools.

Provision is also made for applying to

the crimped lip a pressure which serves to retain the crimped portion of the lip in its turned over position while another portion of the lip is being crimped, which is especially useful while the lip at the toe-portion of the insole is being crimped, and especially the narrow toe portion of pointed shoes. To this end, we employ a presser finger 60 on an arm 61 attached to the framework of the machine, said presser finger being extended over the table and in proximity to the crimping tools when the latter are at the end of their feeding movement, so that the crimped portion of the lip is caused to pass under the presser finger 60, which holds the crimped portion down with sufficient pressure to resist and counteract tendency of the crimped lip to straighten up especially at the toe portion, while adjacent portions of the lip are being crimped.

The features above described, to wit, the oscillating crimping tool, the gage for obtaining a crimped lip of uniform height, and the presser for holding down and retaining the crimped lip in the position in which it leaves the crimping tools, are embodied in a machine in which the operative parts are in the main substantially the same as shown and described in another application Serial Number 44392 filed by us on the ninth day of August, 1915, but by reason of the use of the oscillating tool, the operative parts of the machine are materially diminished and simplified.

Referring to Figs. 1 to 4 inclusive, the shaft 37 on which the cam disk 36 is mounted, is driven from a main shaft 62 by a friction drive, consisting of a driving wheel 63, mounted on the main shaft to rotate therewith and to slide thereon, and a driven member or disk 64 fast on the cam-shaft 37.

The main shaft 62 is journaled in a rocking frame 65, which is acted upon by a spring 166 to normally keep the driving member 63 out of engagement with the driven member or disk 64, but which is compressed to permit the driving member 63 to be engaged with the driven member 64, by moving a projection 165 on a collar 66 from a recess 67 in an annular boss 68 on an arm 69 of the rocking frame, and bringing the said projection into contact with the face of said boss. When the collar 66 is turned so as to engage the projection 165 with the face of the boss 68, a collar or ring 70 is moved on the rod 71 so as to remove the end wall of a slot 72 in said collar, away from a pin 73 on the said rod, thereby enabling a spring 74 on the rod 71 to overcome the spring 166 and rock the frame 65 so as to engage the driving member 63 with the driven member 64. By turning the handle 66 so that the projection 165 enters the cavity 67 as shown in Fig. 2,

the end wall of the slot 72 engages the pin 73, and the spring 166 becomes active and moves the driving member 63 out of engagement with the driven member 64.

The speed of the cam shaft 37 may be varied by moving the driving member 63 on the main shaft toward and from the center of the disk 64, which may be effected by a bell crank lever 76, connected by a link 77 to a treadle (not shown).

The table or work-support 58 and its movable section or gripping jaw 57 are operated substantially as shown and described in detail in the application referred to, and as this construction is not herein claimed, it is deemed unnecessary to describe the same in detail, but merely to state that the movable section 57 of the work-support is held up in its elevated or gripping position by a lever 80, which is acted upon by a path cam, not shown, in the face of the disk 36 opposed to the path cam 35. The lever 80 carries a screw 81, which engages a wedge-shaped bar 82, pivotally mounted in the forked arms 83 of a lever 84, which is mounted on the pivot pin 85 supported by the frame work. The wedge bar 82 supports the spindle 86 of the movable jaw 57, and the said jaw is lowered by a spring 87, when the latter is permitted so to do by the cam which acts on the lever 80.

The table or work-support 58 is lowered at the will of the operator by a treadle, not shown, but which is connected by a link 88 with an arm 89 on the hub of the lever 84, which carries a second wedge-shaped bar 90, upon which rests the spindle 91 of the table 58, which spindle is lowered by a spring 92, when the wedge-shaped bar 90 is moved so as to bring its reduced portion 93 beneath the spindle 91, which is effected by the operator depressing the treadle with which the lever 84 is connected.

The table 58 is lowered to permit the operator to properly position the insole in the machine.

The crimping tools 18, 19, may be rendered inoperative to crimp the lip, at the will of the operator without interfering with the feed of the insole by the crimping tools, by means of a lever 100 provided with a slotted hollow boss 101, into which the cross bar or head 20 of the crimping tools 18, 19, is extended.

The lever 100 is connected with a treadle, not shown, by a link 103, and when the said treadle is depressed, the lever 100 is turned so as to move the crimping tools 18, 19, lengthwise, so as to withdraw them from their operative position with relation to the crimping tool 10, 12, shown in Fig. 6, into their inoperative position shown in Fig. 7, with the result, that the oscillating tool 10, 12 on its forward movement presses the lip

b against the substantially flat lower end of the carrier 21 in which the tools 18, 19, slide, thereby enabling the crimping tools to feed the insole by the portion of the lip which it is desired not to crimp, as, for instance, the shank portion.

The finger 10 of the oscillating tool may and preferably will be provided with a recess or concavity 110 in its end (see Figs. 10 9 and 10), which engages the uncrimped portion of the lip and avoids any danger of tearing the lip when the oscillating crimping tool folds or turns over the uncrimped portion into crimping position.

15 The oscillating crimping tool is herein shown as embodied in a machine in which the crimping tools effect the feed of the insole, but it is not desired to limit the invention in this respect.

20 Claims:

1. In a machine of the character described, in combination, crimping tools constructed and arranged for transversely crimping the lip of an insole, one of said tools oscillating 25 toward and from the other in an arc of substantially small radius to permit the center of oscillation to be located in proximity to the coöperating crimping tool.

2. In a machine of the character described, 30 in combination, crimping tools constructed and arranged for transversely crimping the lip of an insole, one of said tools oscillating toward and from the other, and a presser device arranged with relation to the crimping tools to engage a crimped portion of the lip after it has been crimped by said tools.

3. In a machine of the character described, 40 in combination, crimping tools constructed and arranged to transversely crimp the lip of an insole, and a presser device arranged with relation to the crimping tools to engage a crimped portion of the lip after it has been crimped by said tools.

4. In a machine of the character described, 45 in combination, crimping tools constructed and arranged to transversely crimp the lip of an insole and one of which is oscillated toward and from the other in an arc having a substantially small radius, a common support for said crimping tools, and means for oscillating said oscillating tool.

5. In a machine of the character described, 55 in combination, crimping tools constructed and arranged for transversely crimping the lip of an insole, and means for insuring a substantially uniform height of lip before the latter is crimped.

6. In a machine of the character described, 60 in combination, a stationary gripping jaw to engage the feather of an insole, a gage attached to said gripping jaw and provided with a finger to limit the upward movement of the lip of the insole, and a movable gripping jaw coöperating with said stationary

jaw to firmly grip the feather of the insole 65 between them.

7. In a machine of the character described, in combination, crimping tools constructed and arranged to transversely crimp the lip of an insole, gripping jaws to engage the insole, and means for limiting the height of the lip to enable the insole to be provided with a crimped lip of substantially uniform height throughout its length.

8. In a machine of the character described, 75 in combination, crimping tools constructed and arranged to transversely crimp the lip of an insole, a rock-shaft located in substantially close proximity to one of said crimping tools and to which the other of said 80 crimping tools is attached to rock therewith, and means for rocking said shaft to oscillate the crimping tool attached to it toward and from the other crimping tool.

9. In a machine of the character described, 85 in combination, crimping tools constructed and arranged to transversely crimp the lip of an insole, a rock-shaft to which one of said crimping tools is connected to rock therewith, means for rocking said shaft to oscillate 90 one of said crimping tools toward and from the other, and a backing member for said oscillating crimping tool.

10. In a machine of the character described, 95 in combination, crimping tools constructed and arranged to transversely crimp the lip of an insole, one of said tools oscillating toward and from the other, a rock-shaft to which said oscillating tool is attached, and a pivoted lever carrying both of 100 said tools and said rock-shaft.

11. In a machine of the character described, in combination, an oscillating tool constructed and arranged to engage one surface of the lip of an insole and move the 105 said lip to effect a transverse crimp in a portion of said lip and to turn an uncrimped portion of the lip into crimping position, and a crimping tool to engage the opposite surface of said lip and coöperating with 110 said oscillating tool.

12. In a machine of the character described, in combination, crimping tools constructed and arranged to transversely crimp the lip of an insole and one of which is oscillated about its axial center toward and from the other, a rock-shaft to which the oscillating tool is attached and extended therefrom axially, a lever, means for connecting said lever with said rock-shaft, and 120 means to move said lever to rock said shaft and effect oscillation of said oscillating tool.

13. In a machine of the character described, in combination, crimping tools constructed and arranged to transversely crimp 125 the lip of an insole and one of which is oscillated about its axial center toward and from the other, a movable support for one of the

said tools, a bearing attached to said support, a rock-shaft mounted in said bearing and to which said oscillating tool is attached and extended therefrom axially, and means for 5 rocking said shaft to oscillate said oscillating tool.

14. In a machine of the character described, in combination, crimping tools constructed and arranged to transversely crimp 10 the lip of an insole and one of which is oscil-

lated toward and from the other, a rock-shaft having its center of oscillation extended in the direction of the length of said oscillating tool and to which said oscillating tool is attached, and means for rocking said 15 shaft.

In testimony whereof, we have signed our names to this specification.
